(57) **CLAIM**

The ornamental design for a seat for watercraft, as shown and described.

DESCRIPTION

FIG. 1 is a front elevational view of a seat for watercraft showing our new design;

FIG. 2 is a rear elevational view thereof;

FIG. 3 is a left side elevational view thereof, the right side view being a mirror image of that shown;

FIG. 4 is a top plan view thereof;

FIG. 5 is a bottom plan view thereof;

FIG. 6 is a front left perspective view thereof; and,

FIG. 7 is a rear right perspective view thereof.

The portions of the article shown in broken lines in the Figures form no part of the claimed design.

The subject seat is installed onto watercraft such as water scooters.
